UNITED STATES PATENT OFFICE.

WILSON E. SYMONS, OF NEW YORK, N. Y.

SHOCK-ABSORBING MECHANISM.

1,396,896.

Specification of Letters Patent.

Patented Nov. 15, 1921.

Application filed June 12, 1920. Serial No. 388,496.

To all whom it may concern:

Be it known that I, WILSON E. SYMONS, a citizen of the United States, residing at New York, in the county of New York and State of New York, have invented certain new and useful Improvements in Shock-Absorbing Mechanism; and I do hereby declare the following to be a full, clear, and exact description of the invention, such as will enable others skilled in the art to which it appertains to make and use the same.

My invention relates to shock absorbing mechanism, and while especially adapted for use as the cushioning unit of draft appliances for railway cars and locomotives, is capable of advantageous application wherever it is desired to cushion and absorb great shocks and strains. The primary object of the invention is to provide a mechanism of the character indicated which is strong, durable, efficient and of high shock absorbing capacity, and which is a complete self-contained unit consisting of few and simple parts none of which is frail. Generally stated, this object is accomplished by constructing the mechanism with a casing having upon its interior a plurality of convergent channels within which a plurality of relatively movable wedge members is slideable simultaneously, the wedge members having interposed transversely extending springs which are adapted to be compressed by the relative movement of the wedges, and the inner ends of the wedges engaging a follower which is adapted to energize longitudinally compressible spring means within the casing, said follower and said wedges having engaging faces extending obliquely to the direction of travel of the follower.

There are other features of my invention by which certain advantages are attained, as will hereinafter appear.

In the drawings illustrating the best form in which I contemplate applying the principle of my invention, the scope whereof is pointed out in the claims.—

Figure 1 is a longitudinal sectional view of a shock absorbing mechanism embodying the invention.

Fig. 2 is a view of the mechanism partly in end elevation and partly in section, a portion of the follower being broken away.

Fig. 3 is a section on the line 3—3, Fig. 1.

Fig. 4 is a section on the line 4—4, Fig. 1.

Fig. 5 is a longitudinal central section of the body of the casing illustrated in Fig. 1.

Fig. 6 is a detail sectional view on the line 6—6, Fig. 2.

Fig. 7 is a detail elevation of a portion of the rear end of the casing illustrating the preferred means for detachably connecting the cover plate or closure thereto.

In the drawings, 1 is the body of a casing which is adapted to receive coöoperating spring means and friction elements, said casing member preferably being open at both ends to facilitate the introduction and removal of parts from its interior. The opening at one end of the casing, which for convenience of description may be designated as the inner end, is preferably closed by a detachable cap or cover plate 2 which is rigidly secured to the body of the casing 1, while the opposite, or as it may be called, the outer end of the casing, is provided with a follower 3 which is slideable longitudinally with respect to the body of the casing and which forms a closure for the outer end thereof, said follower 3 being attached to the casing and thereby, in conjunction with the closure 2, serving to retain in assembled position the parts of the mechanism which are within the casing.

The means preferably employed for attaching the members 2 and 3 to the body of the casing 1 are substantially identical, and consist of notched posts entering corresponding longitudinally extending sockets in the body of the casing and secured thereto by suitable keys. The posts 4, which are integrally united to the closure 2, are of cylindrical form, spaced in rectangular relation and enter the rearwardly opening cylindrical sockets 5 in the body of the casing. As shown in Fig. 4, each of these posts is notched or shouldered to provide a passage for the key 6 which extends through a slot 7 in the body of the casing so as to intersect the adjacent socket 5. By this means the closure 2 is rigidly but detachably connected to the body of the casing. The posts 8 with which the follower 3 is integrally provided are also preferably cylindrical in form and each enters and is adapted to reciprocate in a correspondingly shaped forwardly opening socket 9 in the body portion 1 of the casing. As shown in Fig. 6, each of the sockets 9 preferably houses a spring 10 one end of which rests upon the bottom of the socket and the other end of which engages the adjacent end of the post 8. These springs, which are preferably

assembled in the sockets under some initial compression, act as auxiliaries to the main springs, aid in restoring the parts to normal position after they have been actuated in the operation of absorbing shock, and also serve to maintain the over all length of the mechanism by preserving a definite relation of the follower 3 to the outer end of the body of the casing 1 when the parts are in normal position. To connect the follower 3 to the casing so that it may slide with respect to the latter, as well as for the purpose of limiting the outward movement of the follower, the posts 8 are formed with elongated notches 11 (see Fig. 6) which are respectively adapted to receive keys 12 passing through slots 13 in the body of the casing 1. The keys 12 by engaging the posts 8 limit the outward movement of the follower 3, while the slots 11 in the posts are longer than the keys 12 are wide and the follower 3 is thereby permitted to reciprocate with respect to the body of the casing 1 so as to effect compression of the springs 10.

The body of the casing is formed upon its interior adjacent the follower 3 with oppositely disposed convergent faces which are preferably constructed as wedge shaped channels 14 that converge longitudinally toward the interior of the body of the casing. Slidably mounted in the respective channels 14 and conforming to the shape thereof is a pair of wedge members 15 which are adapted to have a relative movement toward and from each other. Spring means interposed between the wedges 15 and compressible by the relative transverse movement of said wedges constantly tend to cause separation of said wedges, while means are provided for limiting the extent to which said wedges may move away from each other. The spring means preferably employed consists of a plurality of transversely extending springs 16 each of which is seated in sockets or spring seats 17 in the wedges 15. The means preferably provided for limiting the separation of the wedges consists of a transversely extending bolt 18 which passes between the springs 16 and extends through suitable apertures 19 in said wedges. In order to accommodate the head of the bolt and its nut, each of the wedges is provided with an appropriately enlarged recess 20 of sufficient depth to allow the wedges to slide in the channels 14 and approach each other without causing the bolt to foul the body of the casing. The bolt 18 preferably extends through the wedges 15 so as to be in alignment with the oppositely disposed channels 14, the strength of the wedges thereby being but little impaired.

At the inner ends the wedges 15 engage a longitudinally movable follower 21 which is yieldingly supported by longitudinal

tending springs 22 and 23 seated upon the end cap or closure 2 of the casing. When the parts are in normal position the opposite ends of the follower 21 bear against stop shoulders 24 formed on the body of the casing at the inner ends of the convergent channels 14.

The engaging faces 25 and 26, respectively, of the follower 21 and wedges 15 extend obliquely to the direction of travel of the said follower, and it is preferred that the outer end faces 27 of the wedges shall also engage the corresponding faces 28 of the follower 3 in planes extending obliquely to the direction of travel of the followers. Such a construction generates greater frictional resistance for the absorption of shock, assists in effecting the return of the parts to normal position, and increases the lateral stability of the mechanism. To prevent too great bursting strain upon the casing the faces 27 and 28 upon the follower 3 preferably have a less transverse inclination than that of the faces 25 and 26.

If desired, the elements of the mechanism by which the frictional resistance is generated may have their rubbing faces or surfaces formed of any suitable metal, such for example as brass, and in the drawings I have illustrated the use of special metal inserts or facings 29 on the surfaces of the wedges 15 which engage the casing and similar inserts 30 for the inclined faces of the inner follower 21. These latter facings, if employed, may conveniently extend to the transverse rib 31 with which said follower may be formed for the purpose of strengthening it and also to provide means for preventing the wedges 15 from approaching closely enough to damage their interposed springs 16. The forward follower 30 also may be provided with a similar transverse rib or stop 32 projecting between the forward ends of the wedges 15 and performing a function similar to that of the rib 31.

In assembling the mechanism the follower 21 is inserted in the body member 1 of the casing and seated upon the stop shoulders 24 thereof. The springs 22 and 23 are thereafter inserted and the rear cap or cover plate 2 of the casing is applied and secured in position by the keys 6, an initial compression thus readily being imparted to the springs if desired. The springs 16 having been interposed between the wedges 15 and the latter having been connected by the transversely extending bolt 18, these members thus assembled are inserted in the outer end of the body of the casing 1 so that the wedges are positioned in the convergent channels 14 with their inner ends bearing against the inner follower 21. The auxiliary springs 10 are then placed in their respective sockets 9, the posts 8 of the follower 3 are entered in said sockets and the keys 12 are entered in said sockets and the keys 12

are passed through the slots 13 in the casing and through the notches 11 in the posts 8, thereby movably attaching the follower 3 to the body of the casing.

5 The construction being substantially as hereinbefore described, its operation will be as follows: For convenience of description, but without intent to impose any limitation thereby, the portion of the mechanism at the 10 right hand end of Fig. 1 will be termed the outer end of the device, while that at the left hand end of Fig. 1 will be referred to as the inner end. Assuming that the shock to be absorbed is applied to the follower 3 at the 15 outer end of the mechanism and that the inner end of the device is in engagement with suitable stops preventing its retreat, (for example, the stops or cheek plates applied to the draft or center sills of a car) the force 20 acting upon the follower 3 forces it and the wedges 15 inwardly so that the latter simultaneously slide in the channels 14 of the casing, thereby displacing the follower 21 from its seat upon the shoulders 24 of the casing 25 and causing a corresponding compression of the main springs 22 and 23. Owing to the inward convergence of the channels 14 in which the wedges slide the latter during their inward movement approach each other 30 and cause the springs 16 simultaneously to be compressed. At the same time also the inward movement of the follower 3 enables the posts 8 thereof to effect the compression of the longitudinally extending auxiliary 35 springs 10 upon which such posts bear. As the wedges 15 in executing their sliding movement in the channels 14 are pressed against the body 1 of the casing not only by reason of the force exerted by the springs 16 40 but also because of the inclined contact of said wedges with the followers 3 and 21, respectively, friction is generated between each of the wedges and the faces of the channels 14 with which they contact, the wedge shaped 45 form of the channels causing the friction due to the pressure of the spring 11 and inclined faces of the followers to be largely augmented. The relative movement of the wedges with respect to the outer follower 3 50 and the inner follower 21, effected by the inclined bearings of the followers upon the ends of the wedges, also produces friction between the followers and wedges which assists in absorbing the shock. When the force 55 causing the inward movement of the follower 3 is withdrawn the springs 10, 16, 22 and 23 expand and in doing so cause the several parts of the device to be restored to normal position, as will be readily understood, the inclined contacting faces of the 60 wedges and followers aiding in the return of the wedges 15 by minimizing any tendency of the latter to stick or bind in the channels 14. If the shock to be absorbed is applied 65 to the cap or cover plate 2 at the inner end

of the casing while the follower 3 is held stationary by pressing against suitable stops or abutments, the operation of the mechanism will be the same as that heretofore described, the only difference being that the 70 relative movement of the wedges 15 with respect to the body of the casing 1 is effected by moving the body of the casing instead of moving the wedges. Upon cessation of the force by which the body 1 of the casing is 75 driven toward the follower 3, the expansion of the springs with which the mechanism is provided restores the parts to their normal position.

I claim:—

1. In a device of the character indicated, the combination with yielding means, of a casing, a plurality of simultaneously movable wedges which are slidable in contact with said casing and are adapted to approach and separate from each other, spring means interposed between said wedges and compressible thereby, and a follower movable with respect to said casing and interposed between said yielding means and said 90 wedges and adapted to be actuated by said wedges, said follower and said wedges having engaging faces extending obliquely to the direction of travel of said follower and converging toward said spring means. 95

2. In a device of the character indicated, the combination with yielding means, of a casing provided with convergent channels of wedge form, a plurality of relatively movable members of wedge cross section simultaneously slidable respectively in the said channels and adapted to energize said yielding means, spring means interposed between said relatively movable simultaneously slid- 100 able members and adapted to be energized thereby, and a follower having wedging engagement with said simultaneously slidable members and interposed between said simultaneously slidable members and said yielding means. 105

3. In a device of the character indicated, the combination with yielding means, of a casing movable in one direction only from its normal position, a plurality of simultaneously movable wedges slidably engaging 115 said casing and adapted to approach and separate from each other, spring means compressible by said wedges upon their movement toward each other, said spring means being compressible in a direction angular to the direction of compression of said yielding means, a follower engaging the inner ends of said wedges and interposed between said wedges and said yielding means, and a follower engaging the outer ends of said 120 wedges, said followers and said wedges having engaging faces extending obliquely to the direction of travel of said followers. 125

4. In a device of the character indicated, the combination with yielding means, of a 130

- 5 follower adapted to energize said means, a casing having interior faces which are inclined with respect to the direction of travel of said follower, a plurality of relatively 65 movable members slidably engaging said inclined faces of the casing and engaging said follower at their inner ends, spring means interposed between and compressible by said relatively movable members, and a follower 70 engaging the outer ends of said relatively movable members, said followers and said relatively movable members having engaging faces extending obliquely to the direction of travel of said followers.
- 10 5. In a device of the character indicated, the combination with yielding means, of a follower adapted to energize said means, a plurality of relatively movable members engaging said follower and adapted to actuate the same, spring means interposed between and compressible by said relatively movable members, and a follower engaging the ends of said relatively movable members opposite the said follower first named, said followers 15 and said relatively movable members having engaging faces extending at different angles to the direction of travel of said followers, the said faces of the first named follower being oblique to its direction of travel.
- 20 6. In a device of the character indicated, the combination with a casing provided with channels of wedge form which converge longitudinally, of longitudinally compressible spring means, a plurality of relatively 25 movable members of wedge cross section simultaneously slidable respectively in said channels and adapted to cause compression of said longitudinally compressible spring means, spring means compressible by said relatively 30 movable members in a direction angular to the direction of compression of said longitudinally compressible spring means, and means interposed between said longitudinally compressible spring means and said 35 simultaneously slidable members tending to separate the latter.
- 40 7. In a device of the character indicated, the combination with yielding means, of a casing having convergent faces upon its interior, a plurality of simultaneously and relatively movable wedges slidably engaging said convergent faces and adapted to cause said yielding means to be energized, means interposed between said wedges and tending 45 to cause their separation, and means extending through said wedges when in assembled position in said casing for limiting the separation of said wedges.
- 50 8. In a device of the character indicated, the combination with yielding means, of a casing, a plurality of relatively movable wedges slidable within said casing, a spring 55 interposed between said wedges and com-

pressible thereby, and means extending through said wedges when in assembled position in said casing for limiting the separation of said wedges. 65

9. In a device of the character indicated, the combination with spring means, of a casing having convergent channels of wedge 70 form, a plurality of relatively movable members of wedge cross section simultaneously slidable respectively in said channels and adapted to cause compression of said spring means, spring means interposed between said 75 relatively movable members and adapted to be compressed thereby, and a bolt extending through and limiting separation of said relatively movable members within said casing, said bolt extending from one of said channels toward another of said channels. 80

10. In a device of the character indicated, the combination with a casing having a plurality of spring sockets, of a spring in each of said sockets, a follower having a plurality 85 of posts respectively extending into said sockets and adapted to compress said springs, spring means within said casing, and a plurality of wedges interposed between said spring means and said follower 90 and adapted to energize said spring means.

11. In a device of the character indicated, the combination with a casing adapted at one end to receive spring means and adapted at the other end to receive friction elements 95 co-operating with said spring means, of spring means and friction elements within said casing, a cover rigidly but detachably secured to said casing and forming a closure for one end thereof, and a follower detachably connected to said casing and slidably movable with respect thereto and constituting a closure for the other end of said casing, said follower being adapted to engage stationary follower stops upon the ear and to 105 limit the emergence of said friction elements from said casing, and said casing being provided with means for limiting the expansion of said spring means. 100

12. In a device of the character indicated, a casing adapted to receive co-operating spring means and friction elements, said casing comprising an open-ended body portion provided at each of its ends with a plurality of recesses, a plurality of cover plates 115 each provided with a plurality of studs, the studs upon the respective cover plates being adapted to enter said recesses at opposite ends of said body portion, and keys respectively engaging said studs and body portion 120 for connecting said cover plates and body portion, one of said cover plates being capable of a limited movement with respect to the other.

In testimony whereof I affix my signature. 125

WILSON E. SYMONS.
